UNITED STATES PATENT OFFICE.

BENJAMIN M. LUPTON, JR., OF JERSEY CITY, NEW JERSEY.

PHOTOGRAPHIC EXPOSURE-METER.

1,144,142.

Specification of Letters Patent. Patented June 22, 1915.

Application filed November 28, 1914. Serial No. 374,362.

To all whom it may concern:

Be it known that I, BENJAMIN M. LUPTON, Jr., a citizen of the United States, and resident of Jersey City, in the county of Hudson and State of New Jersey, have invented certain new and useful Improvements in Photographic Exposure-Meters, of which the following is a specification.

This invention relates to that class of photographic exposure meters whereby the requisite period or periods of exposure of the plates or films under many and varying photographic conditions may be predetermined without chemical tests. In using such devices of prior construction it has been necessary to refer to certain accompanying tables and to compute therefrom the period or periods of exposure to be given to the plate or plates with a certain diaphragm or diaphragms.

It is the object of my invention to provide a compact, self-contained device of simple construction which may be easily and quickly manipulated to indicate the requisite period or periods of exposure under prevailing photographic conditions, and this without recourse to extraneous factor tables or the like.

With this end in view my invention comprises a series of superposed coaxial indicating members bearing coördinated scales of photographic values which when brought into predetermined proximity or registry, by relative rotation of the said members, indicate the period or periods of exposure to be given a particular plate or plates with any specific diaphragm or range of diaphragms for any subject or subjects under various light conditions, as will be hereinafter particularly described and claimed.

In the drawings—Figure 1 is a face view, enlarged, of an exposure meter embodying my invention. Fig. 2 is a back view thereof. Fig. 3 is a transverse vertical section, as on the line 3—3 of Fig. 1. Fig. 4 is a face view of a modified form of the meter.

5 designates a ring, preferably of metal, approximating in diameter and in thickness an ordinary silver dollar and having its periphery similarly knurled or milled. This ring is provided with an internal annular flange 6 upon the upper and lower sides of which are seated two superposed disks 7, 8 respectively, which are snugly encircled by the inner wall of the ring. The peripheral margins of the disks 7, 8 are flush with the

proximate surfaces of the ring, or substantially so, and the face of the upper disk 7 is dished or socketed to receive a third disk 9, whose upper surface is flush, or substantially so, with the encircling facial portion of the disk 7. The three disks, in conjunction with the ring, are connected by a central pivot which is preferably in the form of a rivet or eyelet 10, and hence the disks 7 and 9 are independently rotatable about a common central axis. The structure thus described simulates the form and appearance of a coin or medal, and it may similarly thereto be conveniently carried in the pocket, or it may be attached to a key ring, chain, or the like.

The face of the disk 9 is provided, adjacent its periphery, with a "Time of day" scale *a*, comprising a segmental series of radial graduations, numbered, for example, from 1 to 6 and 6 to 11, as shown, to indicate the day light hours. The face of the disk is also provided adjacent its peripheral edge, with a "Kind of light" scale *b* comprising a second segmental series of radial graduations which are marked to indicate various kinds of light as, for example, from "Bright sunlight" to "Very dull", as shown.

The exposed marginal portion of the disk 7 is provided with a "Month" scale *c*, comprising a segmental series of radial graduations which are numbered to indicate groups of months having approximately corresponding actinic values of day light, as, for example, 1—11 and 12; 2 and 10, and so on, as shown. The graduations of the "Month" scale are spaced correspondingly with those of the "Time of day" scale, so that any of the graduations of the latter may be brought into registry with any of those of the former by the proper turning of the disk 9 on its axis.

The exposed marginal portion of the disk 7 is also preferably provided with a series of radial graduations with several of which the graduations of the "Kind of light" scale are in alinement when the "Time of day" scale is positioned with respect to the "Month" scale. The exposed marginal portion of said disk 7 is also provided, adjacent the "Month" scale, with a radial index or pointer, *d*, the function of which will presently appear.

The exposed face of the ring 5 is provided with a "Plate or film speed" scale *e*, comprising a segmental series of radial gradu-

- 5 tions numbered consecutively with spaced numerals, as, for example, 1/24 to 2, in accordance with the speed equivalents of plates or films, such numerals being so disposed that the proper one is in registry with a predetermined graduation of the "Light" scale when the central disk is adjusted to position the "Time of day" and "Month" scales. The remainder of the exposed face of the ring 5 is provided with 10 a "Speed factor" scale *f*, comprising equal radial spaces consecutively identified with the numbers 1 to 12, which constitute speed factors to one of which the index mark *d* on the disk 7 points when the predetermined plate speed number is properly positioned 15 in respect to the "Light" scale. A segmental portion of the exposed reverse side or back of the ring 5 is provided with a "Speed factor" scale *g*, comprising equal radial spaces consecutively numbered with the speed factors 1 to 12 corresponding with those of the scale *f*, and the remainder of such back is provided with a "Seconds exposure" scale *h* comprising a series of radial 20 graduations numbered consecutively, say, for example, from 1/1000 to 64, to indicate seconds and fractions thereof for exposure 25 of the plates.
- 30 The outer side of the disk 8 is provided, adjacent its periphery, with a "Subjects" scale *i*, comprising a series of graduations, identified with photographic subjects of different light and shade requirements, such, 35 for example, as "Indoor portrait," "Shady banks," &c., as shown. The outer side of the disk 8 is also provided with a "Diaphragm" scale *j*, comprising a series of radial graduations successively identified 40 with the size numbers of various aperture diaphragms or stops ranging from the smallest to the largest aperture. In the present instance two equivalent size numbers are printed in each graduation, as, for 45 example, U. S. 1 and *f*4, &c., as shown.
- 50 The disposition of the subjects on the scale *i*, as respects light and shade requirements, and the order of the speed numbers of the diaphragms on the scale *j* are such, 55 in relation to each other, that when the proper speed factor has been ascertained as above described, and the disk 8 is turned to bring a specific subject to the like factor on the scale *g*, the "Diaphragm" and "Seconds exposure" scales are in close relation to each other, and the proximate numbers of said latter scales indicate the various 60 periods of exposure required for the correlated diaphragms designated on the disk 8.
- 60 Preferably instructions for operating the device are printed thereon, part of such instructions appearing on the face disk 9 and the remainder on the back disk 8, as illustrated.
- 65 The operation of the form of the device

above described is briefly as follows: Assume the month be February; the time be 10 a. m., the light be dull, and the speed of the film be "1/8": The disk 9 is turned on its axis until the space denoted "10" of the "Time of day" scale *a* is opposite the space denoted "2" of the "Month" scale *c*. The ring 5 is then turned until the space of the scale *e* thereon denoting the speed of the particular plate or film in use, say for example "1/8" is opposite the space marked "Dull" of the scale *b* on the disk 9. This done the index *d* on the disk 7 points to the speed factor "7" of the scale *f* on the ring. The device is then inverted and the like speed factor observed on the scale *g* of the ring. Assume now that the subject be "Light foreground", the disk 8 is turned until the designation "Light foreground" of the scale *i* thereon is opposite the ascertained speed factor on the scale *g*, whereupon by reference to the "Seconds exposure" scale on the ring and the "Diaphragm" scale *j* on the disk 8 the various 90 exposures for particular diaphragms or apertures will be apparent, that is, for example, with a diaphragm U. S. 4 or *f*8 the speed will be 1/35 second.

From the foregoing it will be seen that given the speed equivalent of the plate or film to be used, the correct period of exposure (within certain time limits of the day for any month of the year during daylight) or variety of exposures with corresponding diaphragms or stops, can be 100 readily ascertained by merely turning the several members of the device to their proper positions relative to each other in the sequence described. It will also be seen that these exposures take into consideration not only the speed of the plate or film, but also the month of the year with the consequent variation of the actinic value of the rays of the sun, the time of day (for the same reason,) the condition of the atmosphere as respects its effect on the passage of the full power of the sun's light, and the nature or condition of the object or scene to be photographed depending upon the quantity of light it is able to reflect as affecting the photographic plate or film after concentration into a photographic image by means of the camera lens, or other means. My invention thus provides an 110 efficient photographic exposure meter, the use of which requires no computing and no reference to extraneous factor tables.

My improved meter may be made of metal or any other suitable material, or a combination of several different materials, that is, the ring and disks may be composed of metal and have inserted therein celluloid plates or disks with printed characters. The device is, however, preferably made entirely of metal with raised characters produced 125 130

by means of dies or castings and the edges and bearing surfaces of the parts machine finished.

In a meter embodying my invention adapted to be used in connection with plates or films of a particular speed, one of the disks may be omitted, thus further facilitating the procuring of the periods of exposure and corresponding diaphragms or apertures.

10 Such a modified form of the device is illustrated in Fig. 4, by reference to which it will be observed that the disk 7 is omitted, that the "Film or plate speed" scale is absent from the face of the ring, and that the latter bears the "Month" scale *c* and a "Speed factor" scale *f* arranged to accord with the speed equivalent of a particular plate or film. In the present illustration the meter is adapted to use with a "1/6" plate,

20 the several scales being so coördinated that when the disk 7 is turned to set a certain hour of the "Time of day" scale *a* in proper proximity to a character denoting a particular month on the "Month" scale, the various kinds of light indicated on the scale *b* point to the proper factors on the "Speed factor" scale *f*.

I claim—

1. A photographic exposure meter comprising a body, the upper surface whereof bears a scale indicating speed factors, and the lower surface of which body bears two scales whereof one indicates speed factors corresponding with those on the upper surface and whereof the other indicates seconds and fractions of seconds; an upper member on said body movable relatively thereto bearing a scale indicating variable light conditions and also a scale indicating the time of day, said latter scale being coördinated with a suitably-disposed scale indicating groups of months; and a lower member on said body movable relatively thereto bearing two scales whereof one indicates various photographic subjects and the other denotes various diaphragms or stops.

2. A photographic exposure scale comprising a body having thereon three co-axial disks, two of which are superposed on the

upper side of the body and the other of which is on the underside of the body, the upper surface of said body bearing two scales whereof one indicates the various speed equivalents of films or plates and the other indicates speed factors, and the lower surface of said body bearing two scales whereof one indicates speed factors corresponding with those on the upper surface and whereof the other indicates seconds and fractions of seconds, one of said upper disks bearing a scale indicating the time of day and also a scale indicating variable light conditions, and the other of said upper disks bearing a scale indicating groups of months and having also an index in operative relation to the proximate speed factors on the upper surface of the body, and the lower disk bearing two scales whereof one indicates various photographic subjects and the other denotes various diaphragms or stops.

3. A photographic exposure meter comprising an internally flanged ring, and superposed disks seated in said ring having a common axis of rotation, the upper surface of said ring bearing a scale indicating speed factors and the lower surface of said ring bearing two scales whereof one indicates speed factors corresponding with those on the upper surface and whereof the other indicates seconds and fractions of seconds, one of said disks bearing thereon adjacent the upper surface of the ring a scale indicating variable light conditions and also a scale indicating the time of day, said latter scale being coördinated with a suitably-disposed scale indicating groups of months, and another of said disks bearing thereon adjacent the lower surface of the ring two scales whereof one indicates various photographic subjects and the other denotes various diaphragms or stops.

Signed at New York in the county and State of New York this 20th day of November A. D. 1914.
